CHUCK FOR POLISHING MACHINES

Gustave J. Soderberg, Babylon, N. Y.

Application August 30, 1946, Serial No. 693,893

2 Claims. (Cl. 279—41)

1

This invention relates to polishing machines generally and more particularly to portable motorized polishers suitable for polishing automobiles as well as for a great variety of household and industrial uses.

One object of the invention is the provision of such a polishing machine comprising a motor end and a polishing end and a handle positioned intermediate such ends at the center of gravity of the machine so as to eliminate as far as possible all vibration upon the hand of the user thus insuring against the scratching or scoring of the surface being polished.

Another object of the invention is to provide such a polishing device having a simple yet highly efficient chuck for receiving and holding a polishing disk.

A further object of the invention is to provide a device of this nature in which the polishing disk is so maintained in place that it will not be affected by rotation.

Still another object is to provide a polishing machine which is light in weight and will not tire the hand of the user.

Another object of the invention is to produce a polishing machine of the nature described in which the maximum simplicity of construction and operation is secured.

Other objects and advantages will appear as the nature of the improvements is better understood, the invention consisting substantially in the novel arrangement and correlation of parts herein fully described, and illustrated in the accompanying drawings, wherein similar reference characters are used to denote corresponding parts throughout the several views and then finally pointed out and specifically defined in the appended claims.

The disclosure made the basis of exemplifying the present inventive concept suggests a practical embodiment thereof, but the invention should not be restricted to the exact details of this disclosure, and the latter, therefore, is to be understood from an illustrative rather than a restrictive standpoint.

In carrying out the objects of the invention, it was found desirable to provide a polishing machine comprising a substantially light motor at one end and a gear driven chuck at the opposite end for receiving the polishing disk. It was further found advisable to enclose the gearing in a housing and connect same to the motor by means of a handle so placed as to evenly divide the weight of the machine on both sides thereof.

Furthermore, it was found advantageous to provide a polishing disk which comprises a core or backing disk of any suitable material which

2

may be covered or enclosed by a replaceable polishing cloth having an elastically restricted mouth opening so as to be all times securely held on the disk without the danger of its flying off the disk regardless of the speed of its rotation.

The invention will appear more clearly from the following detail description when taken in connection with the accompanying drawings showing, by way of example, preferred embodiments of the inventive idea.

In the drawings:

Figure 1 is a side elevation partly in section of an apparatus embodying the present invention;

Figure 2 is an end view thereof partly broken away looking from the right of Figure 1;

Figure 3 is an exploded perspective view of the polishing disk holding chuck;

Figure 4 is a perspective view of the backing disk;

Figure 5 is a fragmental sectional view taken on line 5—5 of Figure 4;

Figure 6 is a fragmental sectional view of a modified form of backing disk construction;

Figure 7 is a perspective view of one form of polishing cloth or bag used;

Figure 8 is a fragmental sectional view at an enlarged scale taken on line 8—8 of Figure 7; and

Figure 9 is a perspective view partly in section of a brush adapted to be gripped by the chuck of the machine.

Referring now to the drawings in detail, the numeral 10 indicates a polishing apparatus made in accordance with the present invention and comprises generally an electric motor 11 which drives a chuck 12 through gearing 13 enclosed in a split housing 14.

The motor frame or casing 15 is provided with a sleeve 16 which extends into the split housing 14. The split housing 14 comprises a bottom portion 17 and an upper cover 18, the two parts being held together by screws 19. The motor 11 is provided with a shaft 20 which at its free end supports a bevel pinion 21 in mesh with a bevel gear 22 and a shaft 23 disposed at right angles to the motor shaft 20. The shaft 23 is journaled in a ball bearing 24 in the lower housing member 17 said bearing being held in place by a flanged collar 25 secured to the housing member 17 by screws 26.

The shaft 23 carries at its free end a collar 27 which is maintained in place on said shaft by means of a set screw 28 and forms a part of the chuck mechanism 12. The said chuck mechanism 12 also includes a clamping device 29 comprising a pair of jaws or spring plates 30 and 31 joined at the top by a cross member 32 having a screw

50

55

21 which is maintained in place on said shaft by means of a set screw 28 and forms a part of the chuck mechanism 12. The said chuck mechanism 12 also includes a clamping device 29 comprising a pair of jaws or spring plates 30 and 31 joined at the top by a cross member 32 having a screw

3

threaded hole 33 for the reception of a screw 34 which passes through the collar 27 and secures same to the bottom thereof. To further secure the clamping device 29 to the collar and to prevent relative rotary movement between the said parts, the collar 27 is provided with a rectangular slot 35 into which the upper end 29^a of the clamping device fits. The upper end of the clamping device is provided with a pair of upstanding arms or legs 36 which extend into recesses 37 in the sides of the collar 27, said recesses 37 opening into the slot 35 as shown in Figure 3. Screws 38 pass through perforations 39 in the legs 36 and thread into threaded openings 40 in the collar 27.

A screw or bolt 41 is secured to the jaw plate 30 intermediate the ends thereof and passes through a substantially semispherical raised shell portion 42 which is provided with four V shaped notches 43 angularly spaced apart at 90° from each other. A wing nut 44 having a pair of diametrically opposite teeth 45 are adapted to snap into said notches when the wing nut is screwed down upon the screw 41.

As afore mentioned, the machine is adapted to serve a variety of purposes, some of such purposes being accomplished by the use of polishing disks with different kinds of surfaces, such as, abrasive, nappy or smooth.

In Figures 1, 4, 5, 7 and 8 there is shown a polishing disk 46 which preferably comprises a felt backing disk 47 made up of a lower half or section 48 and an upper similar section 49 secured to each other near their peripheries by a row of stitches 50. The upper layer 49 is provided with a slot 51 through which projects a substantially U-shaped tab or tongue 52. The tab 52 may be made of any suitable material. In the Figures 1, 4, and 5 illustration the tab is shown as made of a strip of fabric which is folded over upon itself, the two folded plies being pasted or otherwise secured to each other, the lower ends being bent outwardly to form bases or legs 53 which may be sewn by stitching 54 to the upper disk layer 49.

In Figure 6 there is shown a modified form of the tongue construction and manner of securing same to the upper disk section 49. In this form of the invention the tongue or tab 52^a is made of metal and is secured by bolts and nuts 54 and 55 to the upper layer 49.

The combined disks 48 and 49 may support a polishing or buffing cloth or bag 56 made of suitable material, such as for instance fabric and may have a constricted mouth opening 57. The constricted mouth opening may be formed by inserting and tying at its ends, an elastic cord 58, in a channel 59, the said channel being made from a folded over strip of cloth 60 sewn or otherwise secured to the bag 56 at the mouth thereof.

In Figure 9 there is shown a brush 61 provided with bristles 62 which may be made of wire, hair or of any artificial fibers suitable for the purpose. A tab 52^b is secured to the top 63 of the brush by means of bolts and nuts 64 and 65 respectively.

It will be seen that in all of the various polishing devices, a tab or tongue is suitably secured to such devices, the slot S in each case being wide enough to straddle the screw 41 of the clamping chuck 29. It will also be seen that due to the notches 43 and teeth 45 of the respective clamp elements 42 and 44 the tabs will be firmly held in the chuck as the wing nut 44 will be locked against accidental rotation by the said notch and tooth arrangement. Furthermore, it will be seen that due to the restricted elastically controlled mouth opening the buffing or polishing cloth or bag can-

not fly off the backing disk regardless of the speed of its rotation.

The device as above described is provided with a handle H which is secured to the motor frame 15 and casing portion 18 by screws 66 at the center of gravity of the device and thus eliminate all vibrations upon the hand of the operator thus preventing the scratching or scoring of the surface being polished. A start and stop switch 67 for the motor 11 is carried at the front of the handle as clearly shown in Figures 1 and 2.

From all of the foregoing it will be seen that the present invention provides an inexpensive yet highly efficient polishing device wherein the replaceable polishing or buffing cloth is securely held against a backing disk and will not be adversely affected by rotation. It will further be seen that the device is provided with a positive acting highly efficient clamping device adapted to tightly grip the tongues of the various polishing disks when inserted in position. Likewise it will be seen that the device is non scoring or scratching.

It is apparent that the specific embodiments have been given by way of illustration and not by way of limitation, and that the structure above described is subject to wide variation and modification without departing from the scope and intent of the invention, all of which variations and modifications are to be included within the scope of the present invention.

4

What is claimed is:

1. A chuck comprising a collar, means securing the top of the collar to a rotary member and adapted to be rotated thereby, the collar comprising an upper cylindrical portion coacting with the rotary member and further comprising a lower portion of enlarged diameter, the upper portion having two spaced recesses formed in the rim, the recesses being downwardly extended through the lower portion of enlarged diameter; a clamping device secured to the collar the clamping device comprising a pair of spaced apart plates, a cross member disposed at the top of the plates, an upright arm disposed at either end of the cross member and coacting with the spaced recesses extended through the lower portion of the collar, means releasably securing the upright arms in the recesses, and means adjusting at least the bottom portions of the spaced apart plates relative to each other.

2. A chuck comprising a collar, means securing the top of the collar to a rotary member and adapted to be rotated thereby, the collar having a radially directed slot in the base thereof and longitudinally directed recesses on either side aligned and communicating with the ends of the slot; a clamping device secured to the collar, the clamping device comprising a pair of spaced apart plates, a cross member disposed at the top of the plates, the central portion of the cross member being elevated above the ends and coacting with the radially directed slot in the base of the collar, an upright arm disposed at either end of the elevated portion of the cross member and coacting with the longitudinal recesses, means releasably securing the upright arms in the recesses and the elevated portion of the cross member in the slot, and means adjusting at least the bottom portions of the spaced apart plates relative to each other.

GUSTAVE J. SODERBERG.
